CULINARY MIXER

Roger L. Kelly, Palatine, Ill., assignor to American Home Products Corporation, New York, N.Y.

Filed Jan. 22, 1971, Ser. No. 109,085

Term of patent 14 years

Int. Cl. D7—04

U.S. Cl. D7—153

FIG. 1

FIG. 2

FIG. 3

FIG. 4

FIG. 5

FIG. 1 is a front elevational view of a culinary mixer showing my new design, the back view thereof being a mirror image of said front view.

FIG. 2 is a side elevational view thereof taken from the right of FIG. 1.

FIG. 3 is a partial cross-sectional view showing the underside of the handle taken along line 3-3 of FIG. 1.

FIG. 4 is a side elevational view of the culinary mixer taken from the left of FIG. 1.

FIG. 5 is a partial sectional view taken along line 5-5 of FIG. 1.

I claim:

The ornamental design for a culinary mixer, as shown and described.
